UNITED STATES PATENT OFFICE

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY

HOLDER FOR HEEL-PORTIONS

Application filed December 31, 1931. Serial No. 584,162.

My invention relates to holders for such portions of heels as the top-lifts, it being chiefly concerned with the correct presentation of the lifts or other heel-portions to the nailing mechanism of a heel-attaching machine.

In the securing of heels to shoes, a machine much employed is of the character of that disclosed in Letters Patent of the United States No. 1,157,688, Glidden, October 26, 1915. In this apparatus, a swing-plate is movable alternately between opposite positions in which first a heel-base and then a top-lift are held to receive the action of the machine. Ordinarily, the heel-portions have a conventional form, which allows them all to be properly grasped by the same retaining elements. There has come into use, however, especially in connection with tap-dancing, a form of heel in which a portion of the top-lift is replaced at the rear by a piece of metal, termed a clatter-plate. This may remove so much of the top-lift that the top-lift-fork of the swing-plate or other heel- and top-lift-holder cannot effect stable engagement with it nor correctly locate it with respect to the already attached base. To remove from the swing-plate the regular fork and substitute a special fork when but a limited number of the irregular lifts are to be attached imposes an objectionable burden upon the operator. A purpose of the present invention is to provide for the satisfactory and convenient retention of these cut-away lifts, while permitting also the holding of the usual lifts.

This object I attain, in a holder for heel-portions, by the use of two contact members, herein shown as forks, one of these members being effective to position one type of heel-portion, as a top-lift, and the other another type of a similar heel-portion for attachment to a corresponding work-surface, as the end of a heel-base. I employ a mounting for the second or auxiliary member, which permits its movement from the companion member to an inactive position away from the plane of the work-surface, or toward said companion member into active relation. The mounting of the auxiliary member is such

that the changing of the holder to receive a particular form of heel-portion which is to be operated upon may be accomplished with little effort on the part of the operator, without adding elements to or removing them from the apparatus. In the arrangement which I have chosen to illustrate, the rear contact member or fork for the regular form of lift is fixed in position upon the holding plate for co-operation with the usual breast-bar, and the auxiliary fork is movable into and out of co-operation with said bar. Preferably, the auxiliary fork and fixed fork are provided with engaging members, as interlocking projections and depressions, by which the former fork is temporarily retained in active position. A slotted mounting for the pivot-pin of the auxiliary fork and a spring acting upon this pivot-pin facilitate the change and hold the engaged elements yieldably interlocked.

A single embodiment of the invention appears in the accompanying drawing, in which

Fig. 1 is a top plan view of a swing-plate including my improved top-lift-holder;

Fig. 2, an enlarged perspective view of the top-lift-holder-portion of the plate, with the auxiliary fork in active position;

Fig. 3, a similar view, including fewer elements and with the auxiliary fork swung to its inactive position; and

Fig. 4, a bottom view of a heel with the partial lift and associated plate in place.

In Fig. 1 may be seen the cross-head 10 of the Glidden heel-attaching machine, already referred to, with its die-block 12, in which are the driver- and nail-passages 14. Pivoted at 16 to oscillate in a horizontal plane above the die-block is a swing-plate 18 movable by connections 19 to first present a heel-holder 20 upon the swing-plate above the die-block and then a top-lift-holder 21. The heel-holder includes no novel features and requires no description.

As to the top-lift-holder 21, there is carried by the swing-plate 18 a spanker-plate 22, and upon this is secured a fork 24, the arms of which have outwardly diverging surfaces 26, 26 for engagement with the opposite sides of the curved rear of a top-lift, such as appears

at T in Fig. 3 of the drawing. The top-lift is pressed against the fork-surfaces by a breast-bar 28 guided at 30 for movement toward and from the fork 24, and drawn into contact with the breast-edge of the top-lift by a spring 32. So far, the elements act upon the work in a manner well known. At t in Figs. 2 and 4 is shown a form of top-lift with which may be associated a metal clatter-plate 10 p (Fig. 4). The forward part of the lift t may be the same as that of the lift T, but the rear is cut away, having edges x, x substantially parallel to the breast-edge, and a central projection y in the shape of a portion 15 of a trefoil. Were this applied to the regular fork 24, the corners z, z would contact with the arm-surfaces 26, 26. This would cause the top-lift to be held too far back with respect to the location in which it should be 20 attached, and would tend to give unstable engagement. As a permanent attachment to the holder 21, I provide an auxiliary fork 34 for use with such top-lifts. This fork 34 is arranged to be positioned in front of the 25 fork 24 and has diverging arms, like the fork 24, though these arms are so short that they do not extend to the lift-edges x, x when these are pressed toward them by the breast-bar 28. Consequently, the curved opposite sides 30 of the central lobe of the portion y engages edges 36, 36 of the fork 34, and the top-lift t is located thereby in the same manner as is the top-lift T by the fork 24. The active position of the fork 34 is sufficiently forward from the 35 fork 24 toward the breast-bar, so the top-lift t will be symmetrically presented to the heel-base to which it is to be attached. To allow this auxiliary fork to be held in the correct active position just described and to be shifted 40 therefrom to its inactive relation, leaving the fork 24 free for use, it is mounted in the following manner: Rising from a rearward extension 37 of the fork 24 are spaced lugs 38, 38, in which are openings 40, 40 elongated 45 horizontally. Within these openings lies a pivot-pin 42 projecting from a divided rear portion 44 of the fork 34. The center of the pin is joined by a tension-spring 46 to the rear of the extension 37. When the fork 34 is 50 in use, as appears in Fig. 2, the portion 44 is inclined downwardly and forwardly, and the fork-arms lie at such an angle thereto that they may rest upon the top of the spanker-plate 22. In this respect, they are positioned 55 precisely as is the fork 24, but with their lift-engaging surfaces 36, 36 farther forward than the surfaces 26, 26, this being in proportion to the smaller dimension of the lift t as compared with the lift T. The fork may 60 be locked in this active position by projections 50, 50 from the rear edge of its arms, these projections being drawn by the spring 46 into depressions 52 in the surfaces 26 of the fork 24. The auxiliary fork may readily be moved 65 into its inactive relation by drawing it for-

ward sufficiently to release the projections from the depressions, the pin 42 traveling in the slots 40, and then turning this fork about the axis of the pin until it rests upon the swing-plate at the rear of the fork 24. This is as shown in Fig. 3. The force of the spring 46 holds it against accidental displacement.

Of the general operation of the heel- and top-lift-holder of this invention, in connection with a heel-attaching machine, it may be said that, if a regular top-lift T is to be secured to a heel-base, the auxiliary fork 34 is turned rearwardly to the position illustrated in Fig. 3 of the drawing, being there firmly held by the spring 46. A heel-base is inserted in the holder 20 and a top-lift T in the holder 21, the heel-holder being in position above the die-block. With a shoe jacked in the usual manner and alined with the die-block-openings 14, the machine is started in operation, pressure is applied to the work, and the drivers rise to insert the nails through the heel into the heel-seat. This completes the attachment of the base. When the jack rises, a force applied to the connections 19 shifts the swing-plate from the base-attaching relation to that shown in Fig. 1, in which the holder 21 positions the top-lift T above the die-block-openings. A second operation of the machine establishes pressure upon the work and causes it to force the lift upon the heads of the nails which were left, after the preceding operation, projecting from the base. The attachment of the heel with the regular lift is thus completed. Assuming now that a heel is to be provided with a clatter-plate p, as shown in Fig. 4, the auxiliary fork 34 is turned forward, as illustrated in Fig. 2, being drawn far enough in this direction for the projections 50 to clear the arms of the fork 24, these projections being then drawn back, under the influence of the spring 46, into the depressions 52. This locks the fork 34 in its active position. The top-lift t is applied to the spanker-plate between the breast-bar 28 and the fork 34, the surfaces 36 of said fork engaging the sides of the rearward extension of the portion y of the lift to determine its position with relation to the die-block-openings. The arms of the fork 34 are too short to contact with the edges x of the top-lift, and there is consequently no interference with the correct positioning of the lift. The base is inserted in its holder 20 as before. The nailing of the base and the spanking-on of the top-lift t are carried on precisely as was explained in connection with the attachment of the top-lift T. The clatter-plate p may be applied to the base in contact with the rear edge of the lift and nailed by an independent operation.

Having described my invention, what I claim as new and desire to secure by Letters Patent of the United States is:

1. In a holder for heel-portions, a contact member constructed and arranged to position one type of heel-portion for an attaching operation, a second contact member constructed and arranged to position another type of a similar heel-portion for attachment to a corresponding work-surface, and a mounting for the second member permitting its movement away from the first-mentioned member to an inactive position away from the plane of said work-surface and toward said first-mentioned member into active relation.

2. In a holder for heel-portions, a top-lift-locating member, an auxiliary top-lift-locating member, and a mounting for the auxiliary member permitting its movement between points to the rear and clear of the first-mentioned member and in front of said member in top-lift-receiving position.

3. In a top-lift-holder, a movable plate, a top-lift-fork fixed against movement on the plate, and an auxiliary top-lift-fork pivoted upon the plate and movable toward and from the first-mentioned fork.

4. In a top-lift-holder, a movable plate, a top-lift-fork fixed against movement on the plate, and an auxiliary top-lift-fork movably mounted upon the plate and having shorter top-lift-engaging arms than the first-mentioned fork.

5. In a heel- and top-lift-holder, a swing-plate, a heel-holder carried thereby, a top-lift-holder carried by the swing-plate at one side of the heel-holder, and an auxiliary top-lift-holding member associated with the top-lift-holder.

6. In a holder for heel-portions, a breast-bar, a rear contact member for contact with heel-portions and fixed in position for co-operation with the breast-bar, and a rear contact member movable into and out of co-operation with the breast-bar.

7. In a holder for heel-portions, a movable plate, a breast-bar mounted upon the plate, a rear fork fixed against movement upon the plate, and an auxiliary rear fork pivoted upon the plate to swing into and out of co-operation with the breast-bar.

8. In a holder for heel-portions, a contact member constructed and arranged to position one type of heel-portion, an auxiliary contact member constructed and arranged to

position another type of heel-portion, and a mounting for the auxiliary contact member permitting its movement into and out of active relation, the contact members being provided with means for locking the auxiliary member in its active position.

9. In a holder for heel-portions, a contact member constructed and arranged to position one type of heel-portion, an auxiliary contact member constructed and arranged to position another type of heel-portion, and a mounting for the auxiliary contact member permitting its movement into and out of active relation, the contact members being provided with interlocking projections and depressions.

10. In a holder for heel-portions, a plate, a heel-portion-engaging fork secured to the plate, a slotted mounting carried by the plate, and a heel-portion-engaging fork having a pivot-pin movable in the slot of the mounting.

11. In a holder for heel-portions, a plate, a heel-portion-engaging fork secured to the plate, a slotted mounting carried by the plate, a heel-portion-engaging fork having a pivot-pin movable in the slot of the mounting, and locking means for the movable heel-portion-engaging fork.

12. In a holder for heel-portions, a plate, a heel-portion-engaging fork secured to the plate, a slotted mounting carried by the plate, a heel-portion-engaging fork having a pivot-pin movable in the slot of the mounting, and a spring acting upon the pivot-pin.

13. In a holder for heel-portions, a plate, a heel-portion-engaging fork secured to the plate, a slotted mounting carried by the plate, and a heel-portion-engaging fork having a pivot-pin movable in the slot of the mounting, the forks being provided with interlocking projections and depressions.

14. In a holder for heel-portions, a plate, a heel-portion-engaging fork secured to the plate, a slotted mounting carried by the plate, a heel-portion-engaging fork having a pivot-pin movable in the slot of the mounting, locking means for the movable heel-portion-engaging fork, and a spring acting upon the pivot-pin and rendering said locking means effective.

In testimony whereof I have signed my name to this specification.

JOHN F. STANDISH.
